DESIGN FOR A COMBINED PORCH LIGHT
AND ILLUMINABLE HOUSE NUMERAL IN-
DICATOR

David R. Pennell, Lakewood, Ohio

Application August 6, 1947, Serial No. 140,733

Term of patent 7 years

(Cl. D48—20)

To all whom it may concern:

Be it known that I, David R. Pennell, a citizen of the United States, residing at Lakewood, in the county of Cuyahoga and State of Ohio, have invented a new, original, and ornamental Design for Combined Porch Light and Illuminable House Numeral Indicator, of which the following is a specification, reference being had to the accompanying drawings, forming part thereof.

Figure 1 is a perspective view of the combined porch light and illuminable house numeral indicator embodying my new design and showing the front and one end thereof;

Figure 2 is a perspective view thereof illustrating the front and bottom;

Figure 2 is a perspective view thereof illustrating the front and bottom;

Figure 3 is a rear elevational view thereof;

Figure 4 is a sectional view thereof taken in the direction of the arrows along the line 4—4 of Figure 1;

Figure 5 is an end elevational view thereof; and

Figure 6 is a sectional view thereof taken in the direction of the arrows along the line 6—6 of Figure 1.

The characteristic features of my design reside in the portions shown in full lines.

I claim:

The ornamental design for a combined porch light and illuminable house numeral indicator, as shown and described.

DAVID R. PENNELL.
